CIRCUIT CONTROL MEANS FOR MOTOR VEHICLES

Everett E. Summersett, Hollywood, Fla.

Application January 24, 1948, Serial No. 4,113

3 Claims. (Cl. 315—83)

1

This invention relates to motor vehicle electrical circuits and has particular reference to such circuits, exclusive of the ignition circuit.

In the conventional motor vehicle, circuits have been provided for illumination, including headlights, parking lights and rear lights, such as tail and stop lights, accessories, such as radio, heater and defroster and a conventional starting motor circuit.

It is well known by motor vehicle drivers, that the starting of the engine places a very heavy drain on the battery, especially in cold weather and, when the starter is employed at night, with the usual lights and equipment in use, it frequently happens that the battery is not sufficiently charged to carry the load and failure to turn the motor over results.

An object of this invention is to provide means, operable upon the bringing of the starter into action, to automatically disconnect all lights and accessories during the period of the starter actuation and, upon the release of the starter switch, to cause all circuits to be reestablished.

A further object of the invention resides in automatic circuit control means, operable by bringing the starter into action but, instead of interrupting all the circuits, provision is made whereby certain warning or caution lights may be brought into circuit while the motor is being started, thus relieving considerable strain on the battery, but providing a caution of safety light as a warning to approaching drivers.

Another object is the extreme simplicity of the wiring arrangement, requiring no special tools for installation, employs standard equipment now in use, is cheap to manufacture and install and is highly efficient and beneficial in use.

Other and important objects of the invention will present themselves during the course of the following description, reference being had to the accompanying drawings, wherein:

Figure 1 is a diagrammatic illustration of a circuit embodying the preferred form of the invention and,

Figure 2 is a similar view illustrating a modified form of the invention.

Referring specifically to the drawings and particularly Figure 1, the numeral 5 indicates a conventional motor vehicle lighting control switch, having a plunger 6 adapted to bridge contacts 7 and 8 and contacts 9 and 10. A conductor wire 11 leads from the contact 7 to a pair of parking lights 12, grounded at 13. A conductor wire 14 leads from the contact 8 to one or more tail lights 15, likewise grounded. A conductor wire 16 leads

2

from the contact 9 to a pair of headlights 17, grounded at 18. A circuit breaker, indicated as a whole by the numeral 19 embodies contacts 20 and 21 and 22 and 23. Contact bars 24 and 25, pivotally connected to the contacts 20 and 22 respectively are adapted to swing laterally from the contacts 21 and 23 for making and breaking a circuit therethrough. A conductor wire 26, leads from the battery B, through an ammeter 27, to contact 20, while a conductor wire 28 leads from the contact 21 to the plunger 6 of the switch. A by-pass wire 29 leads from the wire 28 to the contact 22. A conductor wire 30 leads from the contact 23 to various accessories, such as are indicated at 31 and 32, being in this instance a radio and a heater. The means for shifting the bars 24 and 25 laterally, embodies a solenoid winding 33 having a core 34, pivotally connected to the bars 24 and 25. Actuation of the solenoid obviously shifts the bars from the contacts 21 and 23 for interrupting the circuit to the lights and the accessories.

Conventional starter motor is indicated at 35 and includes the conventional shifting solenoid 36. The solenoid 36 is actuated by a conductor wire 37 from the ammeter and includes in its length, the conventional starter switch 38. The solenoid 36 is grounded as indicated. The solenoid 36 carries a bridging contact 39, adapted to bridge contacts 40, normally housed on the starting motor 35. A by-pass wire 41 leads from the wire 37 to one of the contacts 40, while the other contact 40 has direct electrical connection with the winding of the motor. The opposite side of the motor is grounded as indicated. It will thus be seen, that upon a closing of the switch 38, the solenoid 36 shifts its bridging contact 39 across the contacts 40, establishing a flow of electrical energy through the starter motor.

The means for energizing the solenoid 33 comprises a conductor wire 42, leading from the motor contact 40 to one side of the solenoid winding 33, while the opposite side of the solenoid is grounded as indicated. The battery B is grounded, as indicated. It may be found in certain instances, due to various state laws, that warning lights may be required on the rear of the vehicle and to provide for this eventuality, a contact 43 may be included in the gang of contacts for the circuit maker and breaker 19 whereby, when the bars 24 and 25 are shifted, the bar 25 will bridge the contacts 22 and 43. A conductor wire from the contact 43 may extend to any desirable form of safety light.

In the use of this form of the invention, assum-

ing that the switch 5 has been shifted to the head-light contacts 9 and 10 and the circuit controller 19 is in the normal position shown, current is flowing from the battery to the headlights, through a by-pass wire 10' to the tail light and possibly the accessories are being used. When it is desired to start the motor, as when it has become stalled, the starter switch 38 is closed, actuating the solenoid 36 for bridging the contacts 40. Current then flows from the battery through the wires 37 and 41, through the motor 35 to the ground. The flow of electrical energy through the contacts 40, likewise sets up a flow of current through the wire 42 for energizing the solenoid 33, shifting the bars 24 and 25 laterally and interrupting the flow of current to the lights and the accessories. After the motor 35 has started the engine, the switch 38 is released to open position, deenergizing the solenoid 36 and causing the contact 39 to move away from the contacts 40, interrupting the flow of current to the starter motor and to the solenoid 33, causing the bars 24 and 25 to immediately shift to their normal contacting position for establishing the flow of current to the lights and accessories. Thus, the lights and accessories are automatically controlled by the actuation of the starter motor, requiring no other action by the operator than the closing of the switch 38, all movements being controlled thereby.

Referring now to the form of the invention shown in Figure 2, headlights 17, parking lights 12, tail light 15 and control switch 5 are identical to that shown in Figure 1 and the same characters of reference have been applied to these parts. Plunger 6 of switch 5 has connection with the battery B through a conductor wire 44, having an ammeter 46 in its length. The battery B is grounded as indicated. The headlights 17 are connected by a conductor wire 47 with a contact point 48 while a wire 49 connects the contact 9 with a contact 50. The contacts 48 and 50 are normally bridged by a swinging bar 51, held in the normal position by spring means, not shown. A relay winding 52 serves to move the bar 51 from the contact 48 to a contact 53, at such times as the relay is energized. A conductor wire 54 connects the contact 53 with the wire 11, leading to the parking lights 12. The relay 52 is grounded, as indicated. The numeral 55 indicated a conventional starting motor embodying the usual solenoid 56. The solenoid 56 is adapted to be energized by the battery B, through the medium of a conductor wire 57, having in its length the conventional starter switch 58. The solenoid 56 actuates a bridging contact 59 to bridge contacts 60, mounted on the starter casting. One contact 60 is connected with the source of current B, by a conductor wire 61, while the other contact 60 has direct connection with the windings of the motor 55. A conductor wire 62 leads from the motor contact 60 to one side of the relay 52. The motor is grounded as indicated. It is pointed out, that in this latter form of the invention, it is contemplated that all the accessories and the headlights will be turned off during the running of the starter motor, the purpose for this arrangement being to provide sufficient external illumination to the vehicle during the period when the starter is running and to relieve the excessive drain on the battery such as is present when the headlights and accessories are in use.

The operation of this form of the invention is as follows: Assuming that the headlights, tail

light and accessories are in use and it becomes necessary to start the engine. The operator merely presses and closes the starter switch 58, which action energizes the solenoid 56, causing the bridge contact 59 to bridge the contacts 60. Current then flows from the battery through wire 61 to the starter motor. At the same instant, current passes through the wire 62 to the relay 52, causing the bar 51 to move from the contact 48 to the contact 53, thus interrupting the flow of current to the headlights 17. Current then flows from the battery B, through wire 44 to the plunger 6, contacts 9 and 10, wire 49 to contact 50, through bar 51 and contact 53, wire 54 to wire 11, causing the parking lights to burn. Current likewise travels from contact 10, by-pass wire to wire 14 and to tail light 15. Thus a mere actuation of the starter switch 58 results in the automatic changeover from the heavy amperage elements to the lower amperage elements, in this instance being from the headlights and accessories to the parking and tail lights while the starter motor is in operation. Release of the switch 58 to the open position, interrupts the flow of current to the solenoid 56, the motor 55 and relay 52, causing the bar 51 to again move to its normal engaging position with the contact 48, thereby reestablishing the flow of current to the headlights through wire 44, contact 9, wire 49 to contact 50, through bar 51 and contact 48 and wire 11 to the headlights. In either position, current will flow to the tail light. While the accessories have not been indicated as being in the circuit in this form of the invention, it is obvious that they shall connect from the headlight side of the contact 48.

It will be seen from the foregoing that an extremely simple and efficient system of control has been provided for the starting and lighting circuits of a motor vehicle. As an example of the tremendous drain on a vehicle battery, the following figures are cited to indicate the recognized amperes required for the average lighting and accessories. Headlights 14.0 amperes; ignition 1.7 amperes; instrument lights .8 ampere; tail light 1.2 amperes; license light .6 ampere; heater, etc., 7.0 amperes and radio 7.5 amperes. While this invention is not concerned with the ignition circuit, it will be seen that with the lights and accessories in use, a battery must of necessity be well charged to withstand the excessive drain thereon when the starter is brought into use. It will therefore be appreciated, that by momentarily interrupting the lights and accessories while the starter is in use, the battery will be protected and the likelihood of a run-down battery minimized to a large extent. This condition is particularly prevalent in cold climates where engines are normally hard to start. In comparison, summer starting will pull from 125 to 300 amperes, while in winter this will be from 300 to 700 amperes. Another advantage in interrupting the radio while starting is due to the fact that automobile radios are frequently damaged when starting the motor with the radio in use, causing the vibrator to stick. The systems employed are simple and easy to install, are cheap, highly efficient in use and result in a considerable saving in battery damage and recharging.

It is to be understood that the invention is not limited to the precise arrangement shown, but that it includes in its purview, whatever changes fairly come within either the terms or the spirit of the appended claims.

Having described my invention, what I claim is:

1. Control means for motor vehicle electrical

circuits including a source of electrical energy and a starter, vehicle headlights, vehicle parking lights and vehicle tail light, circuits for conducting electrical energy to the several lights, a switch for controlling the circuits, a circuit for conducting electrical energy to the starter, a solenoid for controlling the flow of current to the starter, a source of energy for the solenoid, a switch for controlling the flow of current to the solenoid, a circuit breaker positioned in the circuits to the several lights, a solenoid for actuating the circuit breaker, said last named solenoid energized for breaking the light circuits when the starter is actuated, said solenoids automatically assuming their normal position when the starter is deenergized.

2. Control means for motor vehicle electrical circuits including a source of energy and a starter, headlights, parking lights, tail light and accessories carried by the vehicle, electrical circuits for conducting current from the source of energy to the several lights and accessories, a circuit maker and breaker included in the lights and accessories circuit, a solenoid for actuating the circuit maker and breaker, a circuit for conducting electrical energy to the starter, a solenoid associated with the starter and serving to establish the flow of current to the starter, a circuit for actuating the solenoid, a switch in the circuit for the last named solenoid, a plurality of contacts carried by the circuit maker and breaker, said first named solenoid adapted to be energized upon the establishment of a flow of current to the starter for actuating the breaker to interrupt the flow of current to the lights and accessories, said circuit breaker

when actuated to interrupt the flow of current to the lights, serving to establish a flow of current to a warning light, said circuit maker and breaker automatically being reset upon a deenergization of the starter circuit.

- 5 3. A control means for the electrical circuits of motor vehicles including a battery, a starter, headlights, parking lights and tail light, circuits for conducting electrical energy to the several lights and to the starter, a switch for normally controlling the flow of current to either the headlights and tail light or parking lights and tail light, a solenoid for controlling the flow of current to the starter, an electrical circuit for the solenoid, a switch for the solenoid circuit, a relay, a switch adapted to be actuated by the relay, said relay adapted to be energized upon the establishment of a flow of current to the starter, said relay when actuated adapted to interrupt the flow of current to the headlights and to establish a flow of current to the parking lights, said relay adapted to be deenergized upon an interruption of the flow of current to the starter for automatically interrupting the flow of current to the parking lights and reestablishing a flow of current to the headlights.
